UNITED STATES PATENT OFFICE

HARRY T. KINGSBURY, OF KEENE, NEW HAMPSHIRE

DESIGN FOR A COMBINED FENDER AND TAIL-LIGHT SOCKET FOR TOY AUTOMOBILES

Application filed January 4, 1933. Serial No. 46,730. Term of patent 14 years.

To all whom it may concern:

Be it known that I, HARRY T. KINGSBURY, a citizen of the United States, residing at Keene, county of Cheshire and State of New Hampshire, have invented a new, original, and ornamental Design for Combined Fender and Tail-Light Socket for Toy Automobiles, of which the following is the specification, reference being had to the accompanying drawing, forming part thereof.

In the drawing:—

Figure 1 is a side elevation of the device, showing my new design;

Fig. 2 is a top plan view of the same; and Fig. 3 is a rear view thereof.

I claim:

The ornamental design for a combined fender and tail light socket for toy automobiles, as shown.

In testimony whereof, I affix my signature.

HARRY T. KINGSBURY.
